UNITED STATES PATENT OFFICE

SVEND A. SJOGREEN, OF BERKELEY, AND JAMES W. JOHNSON, OF SAN FRANCISCO,
CALIFORNIA

DESIGN FOR AN EMBLEM HOLDER FOR RADIATOR CAPS

Application filed February 20, 1933. Serial No. 47,274. Term of patent 7 years.

To all whom it may concern:

Be it known that SVEND A. SJOGREEN, a citizen of Denmark, and a resident of Berkeley, in the county of Alameda, State of California, and JAMES W. JOHNSON, a citizen of the United States, and a resident of San Francisco, in the county of San Francisco, State of California, have invented a new, original, and ornamental Design for Emblem Holders for Radiator Caps, of which the following is a specification, reference being had to the accompanying drawing, forming a part thereof, and of which:

Figure 1 is a side elevation of an emblem holder for radiator caps showing our new design;

Figure 2 is a front edge view thereof;
Figure 3 a top plan view; and
Figure 4 a perspective view.

The dominant feature of our design consists in the elongated base member and the oval ring projecting upwards therefrom, and over-hanging, the forward end thereof; the said ring and base member being disposed in the same vertical plane.

We claim:

The ornamental design for an emblem holder for radiator caps, as shown and described.

SVEND A. SJOGREEN.
JAMES W. JOHNSON.
